(57) **CLAIM**

The ornamental design for a juicer tray accessory, as shown and described.

DESCRIPTION

FIG. 1 is a perspective view of a juicer tray accessory, showing our new design;

FIG. 2 is a front elevation view thereof;

FIG. 3 is a rear elevation view thereof;

FIG. 4 is a side view thereof;

FIG. 5 is an opposing side view of FIG. 4;

FIG. 6 is a top plan view thereof;

FIG. 7 is a bottom plan view thereof;

FIG. 8 is an exploded view of the perspective view shown in FIG. 1; and,

FIG. 9 is the perspective view of FIG. 1 shown in use on a base station.

The broken lines show environment and portions of the juicer tray accessory that form no part of the claimed design.

1 Claim, 9 Drawing Sheets
